UNITED STATES PATENT OFFICE.

CHARLES F. BOWMAN, OF KALAMAZOO, MICHIGAN, ASSIGNOR TO KALAMAZOO CORSET COMPANY, OF KALAMAZOO, MICHIGAN.

LEGGING.

1,272,366.

Specification of Letters Patent. Patented July 16, 1918.

Application filed March 12, 1918. Serial No. 221,963.

To all whom it may concern:

Be it known that I, CHARLES F. BOWMAN, a citizen of the United States, residing at the city and county of Kalamazoo, State of Michigan, have invented certain new and useful Improvements in Leggings, of which the following is a specification.

This invention relates to improvements in leggings.

10 The main objects of this invention are:

First, to provide an improved legging of neat and attractive appearance and one which may be quickly put on or removed.

Second, to provide an improved legging 15 which has no projecting or uneven parts on its inner side likely to cause the wearer discomfort or annoyance or to wear the garments over which it is arranged.

Further objects, and objects relating to 20 structural details, will definitely appear from the detailed description to follow.

I accomplish the objects of my invention by the devices and means described in the following specification. The invention is 25 clearly defined and pointed out in the claims.

A structure which is a preferred embodiment of my invention is clearly illustrated in the accompanying drawing, forming a part of this specification, in which:

30 Figure I is a front perspective view of my improved legging laced up or closed.

Fig. II is an inside view of the legging extended or spread out.

Fig. III is an enlarged detail of the outer 35 or overlying edge of the legging.

Fig. IV is a detail edge view of the underlying edge of the legging.

Fig. V is an enlarged detail section on a line corresponding to line 5—5 of Fig. I.

40 Fig. VI is an enlarged detail section on a line corresponding to line 6—6 of Fig. I.

Fig. VII is an enlarged detail vertical section on a line corresponding to line 7—7 of Fig. I.

45 In the drawing similar reference characters refer to similar parts throughout the several views, and the sectional views are taken looking in the direction of the little arrows at the ends of the section lines.

50 In the accompanying drawing certain parts are, for convenience in illustration, shown out of proportion.

Referring to the drawing, the legging, 55 designated generally by the numeral 1, is formed of a plurality of sections seamed to-

gether at 2 to provide suitable shape. The outer or overlapping edge of the legging is designated generally by the numeral 3. The inner or underlying edge is designated generally by the numeral 4 and is preferably 60 provided with a closure flap 5. In the structure illustrated the body material has plait-like folds in its edges, the laps of the fold of the edge 3 being indicated by the numerals 6, 7, and 8, while the laps of the 65 fold of the edge 4 are indicated by the numerals 9, 10 and 11, the lap 11 being extended to form the closure flap 5.

Pocket strips 12 are disposed under the inner laps of the fold and these pocket strips 70 and the fold laps are stitched together at their edges providing longitudinal pockets 13 and 14 for the lace 15 and pockets 16 for the stiffening strips 17 shown conventionally in Fig. V, the stiffening strip pockets being 75 at the inside of the lacing pockets.

Eyelets 18 are secured in the outer or top walls of the lace pockets, there being, in the structure illustrated, eyelets adjacent the tops and bottoms of the pockets and the 80 outer edge has a pair of spaced eyelets centrally thereof. The inner edge has a hook 19 opposed to this central pair of eyelets.

The end 20 of the lace 15 is secured within the pocket 14 of the inner edge and laced 85 outwardly through the bottom eyelet thereof and across the edges and inwardly through the bottom eyelet of the outer edge. The lace then runs longitudinally of the lacing pocket 13 to the lower of the pair of central 90 eyelets through which it is passed and thence inwardly through the upper of the pair of eyelets forming a loop 21 adapted to be engaged with the hook 19. From the upper of the central pair of eyelets the lace runs longitudinally of the pocket 13 to the upper eyelet of this pocket through which it is passed outwardly and across the edges and 95 inwardly through the upper eyelet of the inner edge and thence out through the open 100 edge of the pocket 14 and through the fastening eyelet 22 at the rear of the pocket of the outer edge,—see Fig. I. This eyelet 22 is provided to assist in the fastening of the lace. However, that is not a particular feature of my invention. 105

With this arrangement the stiffening strips support the edges of the leggings so that they cannot collapse and at the same time constitute shields protecting the wearer 110

from the lace and from the fastening members. This arrangement of parts also results in a very neat and attractive appearing legging and one which can be quickly put on or taken off.

Having thus described my invention, what I claim as new and desire to secure by Letters Patent, is:

1. A legging having plait-like edge folds 10 in its body material, the inner lap of the fold of the inner edge being extended into an underlying closure flap, pocket strips disposed on the inner sides of the inner laps of said edge folds, said pocket strips and 15 the fold laps being stitched longitudinally providing lacing pockets and stiffening strip pockets thereunder, lacing eyelets in the top walls of said lacing pockets, the said lacing pockets being open at their front edges opposite 20 said eyelets, the outer edge having eyelets adjacent each end and a pair of spaced eyelets, the inner edge having eyelets at each end and a hook disposed opposite 25 said pair of eyelets of the outer edge, a lacing having one end secured within the lacing pocket of the inner edge and laced out through the bottom eyelet thereof and across the edges and through the bottom eyelet of the outer edge, and thence longitudinally 30 of its lacing pocket and out through the lower and in through the upper of said pair of eyelets providing a hook engaging loop; and thence longitudinally of the lacing pocket and out through the 35 upper eyelet and across the edges and through the upper eyelet of the inner edge, and out of the opening at the edge thereof, and stiffening members disposed in said stiffening pockets and constituting shields for the eyelets and lace. 40
2. A legging having longitudinal lacing pockets at its edges and stiffening pockets thereunder, lacing eyelets in the top walls of said lacing pockets, the said lacing pockets being open at their front edges opposite 45 said eyelets, the outer edge having eyelets adjacent each end and a pair of spaced eyelets, the inner edge having eyelets at each end and a hook disposed opposite 50 said pair of eyelets of the outer edge, a lacing having one end secured within the lacing pocket of the inner edge and laced out through the bottom eyelet thereof and across the edges and through the bottom eyelet of the outer edge, and thence longitudinally 55 of its lacing pocket and out through the lower and in through the upper of said pair of eyelets providing a hook engaging loop; and thence longitudinally of the lacing pocket and out through the upper eyelet and across the edges and through the upper eyelet of the inner edge, and out of the opening at the edge thereof. 60
3. A legging having plait-like edge folds 55 in its body material, the fold laps being stitched longitudinally providing lacing pockets, lacing eyelets in the top walls of said lacing pockets, the outer edge having eyelets adjacent each end and a pair of spaced eyelets, the inner edge having eyelets at each end and a hook disposed opposite 65 said pair of eyelets of the outer edge, and a lacing having one end secured within the lacing pocket of the inner edge and laced out through the bottom eyelet thereof and across the edges and through the bottom eyelet of the outer edge, and thence longitudinally 70 of its lacing pocket and out through the lower and in through the upper of said pair of eyelets providing a hook engaging loop, and thence longitudinally of the lacing pocket and out through the upper eyelet and across the edges and through the upper eyelet of the inner edge, and stiffening members disposed in said stiffening pockets and constituting shields for the eyelets and lace. 75

4. A legging having plait-like edge folds in its body material, the inner lap of the fold of the inner edge being extended into an underlying closure flap, the fold laps being stitched longitudinally providing lacing pockets, lacing eyelets in the top walls of said lacing pockets, the said lacing pockets being open at their front edges opposite 80 said eyelets, the outer edge having eyelets adjacent each end and a pair of spaced eyelets, the inner edge having eyelets at each end and a hook disposed opposite 85 said pair of eyelets of the outer edge, and a lacing having one end secured within the lacing pocket of the inner edge and laced out through the bottom eyelet thereof and across the edges and through the bottom eyelet of the outer edge, and thence longitudinally of the lacing pocket and out through the upper eyelet and across the edges and through the upper eyelet of the inner edge, and stiffening members disposed in said stiffening pockets and constituting shields for the eyelets and lace. 90
5. A legging having plait-like edge folds in its body material, the fold laps being stitched longitudinally providing lacing pockets, lacing eyelets in the top walls of said lacing pockets, the outer edge having eyelets adjacent each end and a pair of spaced eyelets, the inner edge having eyelets at each end and a hook disposed opposite 95 said pair of eyelets of the outer edge, and a lacing having one end secured within the lacing pocket of the inner edge and laced out through the bottom eyelet thereof and across the edges and through the bottom eyelet of the outer edge, and thence longitudinally of the lacing pocket and out through the upper eyelet and across the edges and through the upper eyelet of the inner edge, and stiffening members disposed in said stiffening pockets and constituting shields for the eyelets and lace. 100

- loop, and thence longitudinally of the lacing pocket and out through the upper eyelet and across the edges and through the upper eyelet of the inner edge.
5. 6. A legging having plait-like edge folds in its body material, pocket strips disposed on the inner sides of the inner laps of said edge folds, said pocket strips and the fold laps being stitched longitudinally providing
- 10 lacing pockets and stiffening strip pockets thereunder, lacing members in the top walls of said lacing pockets, a lacing disposed longitudinally of the lacing pocket of one edge and in coacting relation to the lacing mem-
- 15 bers of both edges, and stiffening members disposed in said stiffening pockets and constituting shields for said lacing members and lace.
7. A legging having plait-like edge folds
- 20 in its body material, pocket strips disposed on the inner sides of the inner laps of said edge folds, the inner lap of the fold of the inner edge being extended into and under-
- lying closure flap, lacing members in the top
- 25 walls of said lacing pockets, and a lacing disposed longitudinally of the lacing pocket of the outer edge and in coacting relation to the lacing members of both edges.
8. A legging having longitudinal lacing pockets at its edges and stiffening strip 30 pockets thereunder, the inner edge having an underlying closure flap, lacing members in the top walls of said lacing pockets, a lace disposed longitudinally of the lacing pocket of the outer edge and in coacting relation 35 to the lacing members of both edges, and stiffening members disposed in said stiffening pockets and constituting shields for said lacing members and lace.
9. A legging having longitudinal lacing 40 pockets at its edges, lacing members in the top walls of said lacing pockets, a lace disposed longitudinally of the lacing pocket of one edge and in coacting relation to the lacing members of both edges, and stiffening 45 members disposed under said lacing and constituting shields for said lacing members and lace.

In witness whereof I have hereunto set my hand and seal in the presence of two wit- 50 nesses.
